BY
W. J. Fitz Gerald & Co.
ATTORNEY.

UNITED STATES PATENT OFFICE.

ROBERT O. DUTCHER AND GEORGE HOPE, OF MOROCCO, INDIANA; SAID HOPE
ASSIGNOR TO SAID DUTCHER.

RUNNING-BOARD BRACE.

1,380,046.

Specification of Letters Patent. Patented May 31, 1921.

Application filed January 29, 1920. Serial No. 354,780.

To all whom it may concern:

Be it known that we, ROBERT O. DUTCHER and GEORGE HOPE, citizens of the United States, residing at Morocco, in the county of Newton and State of Indiana, have invented certain new and useful Improvements in Running-Board Braces; and we do hereby declare the following to be a full, clear, and exact description of the invention, such as will enable others skilled in the art to which it appertains to make and use the same.

The present invention relates to means for bracing the running boards of a Ford or similar automobile, whereby to sustain them in position in an effective and substantial manner, and the invention has for its object the provision of a simple and efficient bracing device of that character which can be quickly applied, and having a novel assembly of the component elements.

Another object is the provision of braces or brackets to be carried by the side members of the vehicle frame for supporting the running boards, and a transverse tie bar or cross member assembled with said braces in a novel manner, whereby to brace the running boards one from the other.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawing, wherein:—

Figure 1 is a fragmentary elevation of a Ford or similar automobile chassis showing the bracing structure applied to the frame and running boards.

Fig. 2 is a vertical section on the line 2—2 of Fig. 3.

Fig. 3 is a side elevation showing one brace or bracket and the corresponding tie bar in end view.

The device is shown as being applied to a Ford automobile, although it can be used similarly on other motor vehicles for which it is suited, and the automobile as shown includes the longitudinal side members or beams 4 of the frame, and the running boards 5.

In carrying out the invention, the running boards 5 are supported by braces or brack-

ets 6, provided with attaching portions 7 bearing against the frame members 4 and secured thereto by means of bolts 8 or the like. The braces 6 are curved downwardly, and at their lower ends have arms 9 extending horizontally outward and on which the running boards 5 are seated. These arms 9 have apertures 10 for receiving bolts 11 which extend through apertures in the running board, whereby to clamp the running board on said arms, and the braces are provided at their lower ends with studs 12 depending therefrom below the arms 9 and having nuts 13 screw threaded thereon.

The braces 6 are arranged in pairs at the opposite sides of the frame, and each pair is connected by a transverse tie bar or cross member 14, preferably of channel shape or section with its flanges depending. The lower sides of the arms 9 are inclined, and the end portions of the side bars 14 are similarly inclined, as at 15, to bear upwardly against and overlap the lower surfaces of said arms, and said end portions 15 have apertures 16 to register with the apertures 10 for the reception of bolts 11, whereby to clamp the running boards, arms 9 and portions 13 together. The tie bars 14 are further provided with transverse slots 17 for the passage of the studs 12, so that the nuts 13 can be threaded on said studs for securing and clamping the tie bar upwardly against the braces.

In assembling, the tie bars 14 can be secured to the braces, before the running boards are secured on the arms 9, by placing said bars in position with the studs 12 extending downwardly through the slots 17, and the nuts 15 can then be applied for supporting said bars. The bars can be adjusted transversely of themselves, by the provision of the slots 17, to bring the apertures 16 into registration with the apertures 10, before the nuts 13 are tightened, so that the running board can be conveniently applied and the bolts 11 inserted and secured. Thus, by securing the tie bars to the braces by means of the studs 12, this provides a convenient and substantial construction, and the inclined end portions of the bars also add rigidity to the means for supporting the running boards.

The forward bar 14 is straight and horizontal between front braces 6, whereas the rear bar 14 is dropped or offset downwardly, 110

as at 18, between the rear braces to provide clearance for the brake rods 19.

The present structure can be used in place of the ordinary braces of the running boards, 5 or can be used in conjunction therewith, whichever is desired.

Having thus described the invention, what is claimed as new is:—

1. A running board bracing structure 10 comprising a pair of braces having arms for supporting running boards, a tie bar having portions to bear upwardly against said arms in overlapping relation, and said braces having means for engaging said tie bar and 15 clamping same upwardly against said arms.
2. A running board bracing structure comprising a pair of braces having running boards supporting arms, and depending studs, a tie bar having portions to bear upwardly against said arms in overlapping relation, and slots for the passage of said 20 studs, and means on the studs for clamping

said portions of the bar upwardly against said arms.

3. A running board bracing structure 25 comprising a pair of braces having outstanding arms and studs depending below said arms, a tie bar having portions to bear upwardly against said arms and having transverse slots for the passage of said studs, 30 said portions of the bar and arms having apertures adapted to register for the reception of securing elements to clamp the running boards on said arms, and means on said studs for clamping said portions of the bar 35 against said arms.

In testimony whereof we have signed our names to this specification in the presence of two subscribing witnesses.

ROBERT O. DUTCHER.
GEORGE HOPE.

Witnesses:

HARRY SELLERS,
J. C. MURPHEY.
